(57) **CLAIM**

The ornamental design for a wine stopper, as shown and described.

DESCRIPTION

FIG. 1 is a perspective view of a wine stopper showing the new design.

FIG. 2 is a front view of the wine stopper of FIG. 1.

FIG. 3 is a rear view of the wine stopper of FIG. 1.

FIG. 4 is a side view of the wine stopper of FIG. 1.

FIG. 5 is an opposite side view of the wine stopper of FIG. 1.

FIG. 6 is a top view of the wine stopper of FIG. 1; and,

FIG. 7 is a bottom view of the wine stopper of FIG. 1.

The broken lines are shown for the purpose of illustrating parts of the article that form no part of the claimed design.

1 Claim, 7 Drawing Sheets
